TURBINE WHEEL

David P. Eastman, Chicago, Ill., assignor to
 United Specialties Company, Chicago, Ill., a
 corporation of Delaware

Application September 16, 1946, Serial No. 697,362

4 Claims. (Cl. 253—77)

1

This invention relates to a turbine wheel and to the method of manufacturing such a wheel. It has for one object to provide a method of manufacturing a turbine wheel having a plurality of buckets.

Another object is to provide a turbine wheel construction in which the buckets are held in place by the construction of the wheel and by the other parts which make up the wheel.

Another object is to provide a turbine wheel in which the buckets are held in place without being themselves welded, soldered, brazed or otherwise permanently secured to the wheel body.

Another object is to provide in a turbine wheel means effective to prevent distortion of the parts and loosening or separation of the wheels as a result of centrifugal action.

Another object is to provide a turbine wheel body so arranged that under the influence of centrifugal force, the buckets are effectively gripped and the centrifugal tendency to separate the buckets from the body is effectively counteracted.

Another object of the invention is to provide a turbine wheel having plates which may be formed radially of flat sheet or strip stock.

Other objects will appear from time to time throughout the specification and claims.

The invention is illustrated more or less diagrammatically in the accompanying drawings, wherein:

Figure 1 is a section taken through a portion of a turbine wheel with the bucket shown in elevation;

Figure 2 is a side elevation of one form of the bucket;

Figure 3 is a transverse section taken at line 3—3 of Figure 2;

Figure 4 is a section similar to Figure 1, showing a modified form of bucket-engaging means;

Figure 5 is a plan view of the turbine wheel of Figure 1.

Like parts are indicated by like characters throughout the specification and the drawings.

In the particular form here shown, the turbine wheel includes one or more body members shaped and assembled to engage the buckets. The buckets are generally alike in the two forms of the device.

Each bucket includes a blade portion 1, curved as shown in Figure 1, and provided with attaching portions or extensions 2. In the form shown in Figure 1, the attaching portions 2 are shaped to provide inwardly bent members or portions 3. In the form shown in Figure 4 the attaching members 2 are crimped or otherwise shaped to

2

provide a plurality of curved portions 4. In the form of Figure 2 the inwardly bent portions 3 lie substantially inwardly of the portions 2. In the form of Figure 4, however, the curved portions 4 are alternately positioned on opposite sides of the center line of the portions 2.

In the form shown in Figure 1 the wheel comprises a disc-like member 6 which may be enlarged, as at 7, the portions 6 and 7 being separated by shoulders 8. At its outer edge or periphery the portion 7 is provided with tapered surfaces 9. The member 8 is also provided with annular grooves 10 and with annular shoulders 11 which are of less depth than the grooves 10. When the wheel is assembled, the members 2 of the buckets 1 are shaped to provide the curved portions 3 which lie within the grooves 10 and the flattened portions 12 which lie on the shoulders 11. The inner faces of the members 2 thus conform to the shape of the member 7 with which they are in contact.

Positioned on either side of the wheel member 6 are plates 13. These plates are shaped to conform to the shape of the members 6 and 7 and 25 to contact the shoulder 8. Each of them is provided with a laterally bent edge member 14. Annuli 15 may be secured on the outer face of each of the members 13 and are held in place by rivets 16 which pass through them and the 30 members 13 and 7. Each annulus 15 is cut away, as at 17, and is provided with a peripheral extension 18. Each peripheral extension 18 is in contact with the inner face of one of the members 14. The cut away portion 17 provides clearance between the annulus 15 and the corresponding portion 14.

19, 19 are members which are annular in shape and may be continuous or discontinuous. Each of them lies within the annular groove defined by 40 the curved portions 3 of its associated buckets and is held in place therein by the side plates 13 but need not be secured to those members and are merely held firmly in position when the assembly is riveted together by means of the 45 rivets 16.

As above pointed out, the form of Figure 4 differs from that of Figure 1 primarily by the difference in the shape of the extensions 2. The central plate 6 is provided with a relatively small enlargement 20 and the portion 21 closest to its edge is provided with one or more annular grooves or depressions 21, between each of which remains a raised portion 22. Plates 23 are positioned one on each side of the member 6 and each of them is provided with an internal groove 24 within

which the enlargement 24' fits. A clearance is provided between the periphery of the enlargement, as shown. Each of the plates 23 is provided with one or more annular grooves or depressions 25 between each pair of which a raised portion 26 remains. The grooves 25 of the plates 23 are formed or positioned with respect to the grooves 21 of the member 20 to alternate so that a crimped or sinuous passage remains between the member 20 and each of the members 23 within 10 which the curved portions 4 of the members 2 of the buckets may be tightly received.

Each of the members 23 is provided with a lateral extension or flange 27 and annuli 28 may be positioned one adjacent each of the plates 23. 15 The annuli, if present, are each provided with a peripheral extension 29 and a cut away portion 30.

The wheel in the form of Figure 4 is finally secured together by rivets 31.

Although I have shown an operative form of my invention, it will be recognized that many changes in the form, shape and arrangement of parts can be made without departing from the spirit of the invention, and my showing is therefore to be taken as, in a sense, diagrammatic.

In particular, the invention is not limited to the exact details shown. The two forms of the invention are generally the same. Each includes wheel members shaped to grip parts of the buckets so that when the wheel is assembled, the bucket parts are held in place on the wheel. The bucket parts are curved, bent or otherwise so shaped that they cannot be displaced from the wheel during operation as a result of centrifugal force. The members 15 and 28 may or may not be used, and if used, they might be welded or otherwise permanently secured to the parts 13 and 23, respectively. The exact curvature or contour of the members 2 in either form of the device is optional and the invention is not limited to the particular curvature or shapes shown. The buckets are preferably made from flat sheet or strip stock. They are cut to the required plane and the bucket portion is shaped to the contour shown in Figure 3 or to any desired contour. The attaching portions 2 are cut from the body of the sheet or strip stock and are integral with the blade portion.

The use and operation of this invention are as follows:

Whichever form of the invention is to be used, the wheel parts are shaped as shown and the buckets are shaped as shown, and the parts are then ready for assembly.

In the form of Figure 1, the buckets are fitted over the outer edge of the member 1 and are shaped or bent to lie in close contact with the inclined surfaces 9 and to fit closely into the grooves 10 and to lie in close contact with the grooves or shoulders 11. The members 19 are then put in place, one in each of the grooves defined by the portions 3 of the bucket members 2.

Now the plates 13 are put in place and the annular members 15 may, if desired, be put in place and the entire structure is riveted together by the rivets 16. Obviously other means might be used for fastening the various parts of the structure together.

The wheel of this form of the invention, when put in use, is of course subjected to centrifugal force, which has a tendency to throw the buckets out of place or to separate them entirely from the wheel body. Obviously this cannot occur if the parts are not separated or distorted from the

position and shape of Figure 1. One way in which separation might occur would be for the members 13 to spread slightly or to become distorted otherwise, or to "grow" so as to provide some clearance or at least some looseness which would permit the members 2 to be pulled out of engagement with the wheel. The wheel has, therefore, been shaped to provide means for counteracting any tendency to distort under centrifugal force which might permit loosening of the blades. Thus the portions 14, under the influence of centrifugal force, tend somewhat to tilt inwardly and in doing so they exert an inward force in the direction of the bucket members 2, 3 and thus force the members 19 increasingly against the members 2, 3. This effect counteracts any tendency to distort in the direction of loosening the buckets and utilizes centrifugal force to hold the buckets ever tighter during rotation. The members 14 might be considered counterweights for this purpose.

The plates 13, and in particular the portions 14, have been made unsymmetrical in order to create structures which, under the influence of centrifugal force, will exert an inward pressure in the direction to hold the bucket members 2, 3 against distortion and against escape.

Obviously the area of the members 18 might be increased and the clearance or cut away portions 17 might be eliminated so that the edge of each plate 15 would be in contact with the portion 14 throughout its entire area.

The annular members 15, if present, serve to augment the counterweight effect of the members 14. Since they are in contact with those members only along the limited area of the portion 18 which is positioned on the outward side of the members 15, whatever effect the members 15 impart under the influence of centrifugal force is exerted upon the outer portion of each member 14.

Obviously, although the forces discussed may be very large, the relative movements of the parts are small. However, they are sufficient to hold the blades in place under all working conditions. It is important to realize that the buckets are neither welded, brazed nor otherwise permanently fastened to the wheel. They are merely engaged with the parts of the wheel and those parts are so shaped that centrifugal force is at all times effective to hold the buckets firmly in place. In the form of Figure 1 the load of the buckets is carried entirely on the central member 6 and on its enlargement 7.

The method of assembly of the form shown in Figure 4 is the same as that previously described, except that there are no members comparable to the members 19 of Figure 1. After the plate 6 has been formed and the grooves 21 formed in the portion 20, the buckets are put in place and the curved portions 4 are registered with the grooves and raised portions of the member 20. Thereafter the outer plates 23 are put in position and their grooves 25 and raised portions 26 register with the corresponding grooves and depressions of the bucket portions 2. The members 27 of the plates 23 correspond to the members 14 of the plates 13 and the annular members 28 correspond to the annular members 15. Under the influence of centrifugal force, the members 27 tend to move inwardly and thus exert a pressure inwardly against the bucket members 2 and the curved portions 4 of those members. The annular members 28, through their reduced por-

tions 29, augment this effect by exerting a force outwardly on the portions 21.

The form of Figure 4 differs further from the form of Figure 1 in that the load of the buckets is carried approximately one-half upon the portion 20 of the central member 6 and approximately one quarter on each of the plates 23. It will be noticed that the center line of each of the members 2 contacts the peaks formed in the parts 20 and 23 by the alternate grooves and raised portions 21, 22 and 25, 26, respectively.

The rings or members 15 or 28 may be used to balance the turbine wheel as they are themselves not highly stressed. Thus the rings 15 or 28 may, after the wheel is assembled and tested for balance, be altered slightly to correct balancing. This may be done by boring out or otherwise removing parts of the metal. The flanges 14 and 27 might also be shaped or otherwise treated to accomplish balancing of the wheel.

In Figures 1 and 4, a clearance is shown between the inner or central plate and the outer plates. This clearance is exaggerated in the drawings, and it may in certain cases disappear entirely when the wheel is riveted together. The parts are shaped to provide this initial clearance prior to riveting or other permanent fastening. This is to insure a tight contact between the members 2 of the buckets and the parts which engage them. If this initial clearance, for example between the members 7 and 13, were not provided, the wheel when assembled might not grip the bucket parts 2 with sufficient tightness; therefore, the clearance is provided to make sure that in the assembled wheel an adequately tight grip is effected upon the bucket parts 2 by the members which contact them.

I claim:

1. In combination in a turbine wheel, a central wheel member, a plurality of buckets, said buckets provided with parts shaped to interfit with said wheel member, and a pair of holding members positioned one on each side of said wheel member, and each in engagement with a part of said buckets, said holding members provided with portions adapted, under the influence of centrifugal force, to move to exert an inward pressure upon said buckets to hold them in place, and additional counterweights positioned on each side of said wheel, and adapted, under the influence of centrifugal force, to effect through said holding member an inward pressure on said buckets.

2. In combination in a turbine wheel, a central wheel member, a plurality of buckets, said buckets provided with parts shaped to interfit with said wheel member, and a pair of holding members positioned one on each side of said wheel member, and each in engagement with a part of said buckets, said holding members provided with portions adapted, under the influence of centrifugal force, to move to exert an inward pressure upon

said buckets, to hold them in place, and additional counterweights being shaped each to bear against an outer portion of its respective holding member, and adapted, under the influence of centrifugal force, to effect through said holding member an inward pressure on said buckets.

3. In combination in a turbine wheel, a central wheel member, a plurality of buckets, said buckets provided with parts shaped to interfit with said wheel member, and a pair of holding members positioned one on each side of said wheel member, and each in engagement with a part of said buckets, said holding members provided with unsymmetrical portions extending outwardly therefrom and adapted, under the influence of centrifugal force, to move to exert an inward pressure upon said buckets to hold them in place, and additional counterweights positioned on each to bear against an outer portion of its respective holding member, and adapted, under the influence of centrifugal force, to effect through said holding member an inward pressure on said buckets.

4. In combination in a turbine wheel, a central wheel member, a plurality of buckets, said buckets provided with parts shaped to interfit with said wheel member, and a pair of holding members positioned one on each side of said wheel member, and each in engagement with a part of said buckets, said wheel member and holding members being secured together, said holding members provided with unsymmetrical portions extending outwardly therefrom and adapted, under the influence of centrifugal force, to move to exert an inward pressure upon said buckets to hold them in place, and additional counterweights positioned on each side of said wheel, said counterweights being shaped each to bear against an outer portion of its respective holding member, and adapted, under the influence of centrifugal force, to effect through said holding member an inward pressure on said buckets.

DAVID P. EASTMAN.
